UNITED STATES PATENT OFFICE

158,837

LIFTER TONGS

John Clark Brown, Upper Montclair, N. J.

Application September 10, 1948, Serial No. 148,530

Term of patent 14 years

(Cl. D44—4)

To all whom it may concern:

Be it known that I, John Clark Brown, a citizen of the United States, residing at 18 Waterbury Road, Upper Montclair, county of Essex, and State of New Jersey, have invented a new, original, and ornamental Design for a Lifter Tongs, of which the following is a specification, reference being had to the accompanying drawing, forming part thereof.

In the drawing:

Figure 1 is a plan view of a lifter tongs, showing my new design;

Fig. 2 is a side elevational view looking in the direction of the arrows 2—2 of Fig. 1; and

Fig. 3 is an end view looking in the direction of the arrows 3—3 of Fig. 1.

I claim:

The ornamental design for a lifter tongs, as shown.

JOHN CLARK BROWN.
